COMBINATION TOOL

Frank S. Horechney, Milwaukee, Wis.

Application May 23, 1938, Serial No. 209,576

3 Claims. (Cl. 81—180)

My invention relates to tools and includes among its objects and advantages the provision of an improved combination and convertible tool.

In my Patent 2,076,462, issued April 6, 1937, 5 I illustrate a combination and convertible tool in which clamping jaws are movably related and designed to constitute anchoring means for various tool accessories. In the patent, the jaws are actuated through the medium of a screw, but 10 the range of adjustment is limited.

An object of my invention is to provide a tool of the type described in which auxiliary clamping means may be associated with the jaws and so arranged as to accommodate relatively large 15 work.

Another object is to provide a tool of the type described in which right angular reaches are associated with the jaws and in which the reaches constitute mounts for tool supports to 20 the end that various tools may be associated therewith. The tool supports are adjustably connected with the right angular reaches, which reaches are so arranged as to accommodate relatively large work together with means associated therewith for indicating the spacing in 25 terms of inches or other values.

Another object is to provide a tool embodying a novel mount in combination with a series of novel attachments or tools therefor.

30 In the accompanying drawings:

Fig. 1 is a plan view of the tool illustrated in the above-identified patent illustrating my invention associated therewith with certain parts illustrated in section for the sake of clearness;

35 Fig. 2 is a view taken along the line indicated by 2—2 of Fig. 1;

Fig. 3 is a sectional view along the line 3—3 of Fig. 1;

Fig. 4 is a plan view of my invention showing 40 novel files connected therewith;

Fig. 5 is a similar view showing another method of mounting the files;

Fig. 6 is a perspective view of a brush;

45 Fig. 7 is a perspective view of a different form of brush;

Fig. 8 is a perspective view of a different brush and mount therefor;

Fig. 9 is a view illustrating clamp blocks for 50 connection with the tool;

Fig. 10 is a perspective view of one of the clamp blocks;

Fig. 11 is a perspective view of a cutting block;

55 Fig. 12 is a plan view of files designed for connection with the tool;

Fig. 13 is a perspective view of one of the files illustrating the mount therefor;

Fig. 14 is a view illustrating protective pads connected with vise elements which may be connected with the tool;

Fig. 15 is a perspective view of one of the protective blocks; and

Fig. 16 is a perspective view of a wedge element.

In the embodiment selected to illustrate my invention, I make use of a tool 10 including jaws 12 and 14. Jaw 14 includes an H-shaped opening 16 and right angular ribs 18 provided with threads 20.

Jaw 12 includes a bar 22 which is H-shaped in 15 cross section and slidably receivable within the opening 16 in the jaw 14. The ribs 18 associated with the jaw 14 are slidably receivable within the grooves 24 in the bar 22. Jaws 12 and 14 are arranged in parallel relation but in right angular 20 relation to the longitudinal axis of the bar 22. Meshing with the threads 20 is a screw 26 fixedly connected with a shaft 28 having its end 30 loosely positioned in a bore 32 in the inner end of the bar 22. The shaft 28 includes a collar 34 lying adjacent the inner face of the end 36 of a rectangular tube 38 which encloses the bar 22 and the ribs 18. The ribs 18 fit snugly between the bar 22 and two inner faces of the tube 38 but are slidably related thereto. Upon the outer 30 end 40 of the shaft 28, which extends through an opening in the wall 36, I fixedly connect a hand wheel 42 which may be provided with a handle 44 for turning purposes. The boss 46 on the wheel 42 has abutting relation with the 35 outer face of the ends 36 so that the boss and the collar 34 restrain the shaft 28 from longitudinal movement, but the shaft is free to rotate for imparting movement to the jaw 14 longitudinally of the bar 22.

Bar 22 is fixedly related to the tube 38 by screws 48. In Fig. 3, I illustrate one of the screws as having a head 50 countersunk in the wall 52 of the tube and its end 54 as having threaded relation with the wall 56 of the tube. Jaws 12 and 45 14 are of the same thickness, but each is slotted inwardly of each end, as at 58, to provide parallel flanges 60. Thus, each jaw includes two sets of parallel flanges 60. The flanges are perforated at 62 for the reception of bolts 64 having 50 threaded relation with some of the jaws, as at 66 in Fig. 2. Various types of tools having flanges shaped to fit within the slots 58 may be connected with either or both jaws. The tool flanges or holders would of course have perforations for 55

the reception of the bolts 84. Jaws 12 and 14 are illustrated in their maximum separated relation in Fig. 1, but the threads 20 are of sufficient length to permit the jaws to be moved in abutting relation. In addition to constituting supports for tools, the jaws 12 and 14 may be used for clamping purposes, but the size of work is limited to the reach of the threads 20. The structure so far described is identical with that disclosed in the above-identified patent.

My invention constitutes auxiliary tool supports and clamping means which may be connected with the jaws 12 and 14 so as to accommodate work of relatively large proportions. I make use of bars 68 which have flanges 70 shaped to fit snugly within the slots 80. The flanges 70 are bored for the reception of the bolts 84. The bars 68 are arranged in axial alignment and in parallel relation with the longitudinal axis of the tool, and each bar is provided with a serrated or toothed surface 72. Upon the toothed face of each bar I mount a supporting block 74 having complementary teeth 76 co-operating with the teeth 72 to restrain the blocks from relative movement on their respective bars 68. Each block is provided with an opening 78 for the reception of a bolt 80 extending through a slot 82 in the block. The bolt 80 may be provided with a squared reach 84 fitting snugly within the slot 82 to restrain the bolt from rotary movement. The opposite end of the bolt is provided with a wing nut 86. Both bars 68 and the blocks associated therewith are identical in construction.

Each block 74 includes an octagonal opening 88 for the reception of the similarly shaped shank 90 of a clamp jaw 92 or other tool. A set screw 94 may be associated with each block for fixedly connecting the shank 90. Bars 68 project in opposite directions so that the clamp members 82 will lie beyond the work receiving capacity of the jaws 12 and 14. The block 74 may be easily and quickly adjusted by merely loosening the bolts 80 and shifting the blocks to the desired positions. Upon the bars 68 I provide scales 98 in terms of inches, which facilitate determining proper spacing between the members 82 or other devices that may be associated with the jaws 12 and 14. Each block may be provided with a line 98 for registration with the division lines of its respective scale 98.

Fig. 4 illustrates circular files 100 having shanks 102 shaped to fit inside the sockets 88 in the blocks 74. Fig. 5 illustrates the same files having their shanks 102 fitting in sockets 104 having flat extensions 106 shaped to fit between the flanges 60 of the jaws 12 and 14.

Fig. 6 illustrates a brush 108 in which the bristles are anchored to a central support 110 terminating in a shank 112 shaped to fit the sockets in the block 74 or the sockets 104. Brush 114, of Fig. 7, is different only in that it is semi-circular. In Fig. 8, the brush 116 includes a back 118 provided with a flange 120 shaped to fit between the bars 122 connected with the shank 124. Flange 120 is provided with openings 126 which may be brought into registration with similar openings 128 in the bars 122, after which bolts 130 are slipped through the aligned openings and the nuts applied for clamping the brush 116 in position. Shanks 112 and 124 fit both sockets 88 and 104.

Fig. 9 illustrates pressure blocks 132 provided with flanges 134 shaped to fit between the flanges 60 of the jaws 12 and 14. The pressure blocks may be employed for clamping purposes for applying pressure.

Fig. 10 illustrates a perspective view of one of the blocks. The flanges 134 are provided with openings 136 for the reception of the bolts 84. Fig. 11 illustrates the block 138 as having a cutting blade 140 which may be used in connection with one of the blocks 132 for cutting purposes. At the same time, the blade 140 may function as a wedge. Block 138 includes a flange 142 corresponding to the flanges 134.

In Fig. 12, I illustrate two file units 144 as being associated with mounts 146 having flanges 148 arranged to fit between the flanges 60 of the jaws 12 and 14. Fig. 12 illustrates the specific construction of one of the mounts for the files. Each file includes ribs 150 arranged to fit inside troughs 152 carried on plates 154. Each plate 154 includes a flange 156. The file 144 is assembled with the two units illustrated in Fig. 13, at which time the flanges 156 abut the ends of the file 144 with the flanges 158 having abutting relation to define the flange 148 of Fig. 12. The flanges 158 are provided with openings 160 for the reception of the screws 84.

Fig. 14 illustrates vise elements 162 having flanges 164 arranged to fit between the flanges 60 of the jaws 14 and 12. Protective coverings 166 are mounted on the vise elements 162 and are made secure by bolts 168. The protective coverings 166 may comprise semi-rigid material, such as rubber. Fig. 15 illustrates one of the coverings.

In Fig. 16 I illustrate a wedge-shaped element 170 having a shank 172 corresponding to the shanks previously described. Element 170 tapers to a point 174 and is provided with an opening 176. The shanks 172 may be connected with the sockets 88 or 104 and may be used for spreading purposes.

In Fig. 4, I illustrate the jaw 12 as including a socket 178 for receiving one end of a pale 180 having a pointed end 182. Jaw 12 includes a set screw 184 for making the pale secure.

Without further elaboration, the foregoing will so fully describe my invention that others may, by applying current knowledge, readily adapt the same for use under various conditions of service.

I claim:

1. In a tool of the type described including parallel and relatively movable supports and means for moving the supports toward and away from each other, bars detachably connected with said supports in right angular relation therewith, said bars being axially aligned and projecting in opposite directions, tool supports mounted on said bars, said bars and the tool supports being provided with cooperating surface irregularities to restrain the tool supports from relative movement on the bars, and means for drawing the tool supports into pressure relation with their respective bars to clamp the tool supports thereon.

2. In a tool of the type described including parallel and relatively movable supports and means for moving the supports toward and away from each other, bars detachably connected with said supports in right angular relation therewith, said bars being axially aligned and projecting in opposite directions, tool supports mounted on said bars, said bars and the tool supports being provided with cooperating surface irregularities to restrain the tool supports from relative movement on the bars, means for drawing the tool supports into pressure relation with their respective bars to clamp the tool supports thereon, said means comprising slots in said

bars, and tightening screws extending through the tool supports and said slots and cooperating with said bars and the tool supports for drawing the latter against the bars.

- 5 3. In a tool of the type described including parallel and relatively movable supports and means for moving the supports toward and away from each other, bars detachably connected with said supports in right angular relation therewith, said bars being axially aligned and projecting in opposite directions, tool supports mounted on said bars, said bars and the tool supports being provided with cooperating surface irregularities to restrain the tool supports from relative move-
10 ment on the bars, means for drawing the tool supports into pressure relation with their respective bars to clamp the tool supports thereon, said first-mentioned supports having slots, said bars having flanges adapted to be inserted in 5 said slots, and bolt means extending through aligned openings in said first-mentioned supports and said flanges for fixedly connecting the flanges with the first-mentioned supports, said tool supports when positioned at their closest 10 spacing on said bars being spaced apart a distance greater than the spacing between the first-mentioned supports.

FRANK S. HORECHNEY.
